Des. 215,207
Patented Sept. 16, 1969

215,207

CAR MAT

David Atkin, London, England, assignor to The Cannon
Rubber Manufacturers Limited, London, England

Filed June 6, 1968, Ser. No. 12,242

Claims priority, application Great Britain May 18, 1968

Term of patent 7 years

Int. Cl. D12—14

U.S. Cl. D14—5

Fig. 2.

Fig.4.

Fig.6.

FIGURE 1 is a top plan view of a car mat, showing my new design, it being understood that the rear is the same;

FIGURE 2 is a side elevational view thereof;

FIGURE 3 is an enlarged fragmentary plan view of the area III of FIGURE 1;

FIGURE 4 is a cross-sectional view thereof taken on the line IV—IV of FIGURE 3;

FIGURE 5 is an enlarged fragmentary plan view of the area V of FIGURE 1; and,

FIGURE 6 is a cross-sectional view thereof taken on the line VI—VI of FIGURE 5.

I claim:

The ornamental design for a car mat, substantially as shown and described.
